UNITED STATES PATENT OFFICE.

LAZARD KAIN, OF HAMILTON, OHIO, AND ADAM SPECK, OF DETROIT, MICHIGAN, ASSIGNORS TO F. & L. KAIN & BROS., OF HAMILTON, OHIO.

DESIGN FOR A GAS-RADIATOR.

SPECIFICATION forming part of Design No. 24,557, dated August 18, 1895.

Application filed May 31, 1895. Serial No. 551,336. Term of patent 14 years.

To all whom it may concern:

Be it known that we, LAZARD KAHN, a resident of Hamilton, Butler county, Ohio, and ADAM SPECK, a resident of Detroit, Michigan, citizens of the United States, have invented a certain new and original Design for a Gas-Radiator, (Case B,) of which the following is a specification.

Our design for a gas-radiator is shown in the accompanying drawing, which represents a perspective view of the radiator. The vertical radiator-tubes 9 are surmounted by horizontal top 10 and rest upon the horizontal base 1 and bear ornamental escutcheons 6, the ornamental base and escutcheons having the characteristics hereinafter mentioned and forming the leading features of our design. The base 1 is round-cornered and bears a lower band 3 of short vertical ribs. The base bears top nozzles 2 for the radiator-pipes, which are banded by irregular bark-like ver-

tical flutings. The surfaces 5 of the base between the band 3 and nozzles 2 are substantially a quarter-circle in vertical section and are ornamented by foliate scrolls in low relief. The radiator-tube escutcheons 6 have each a pair of substantially rectangular piercings 7, separated by an ornamental cross-bar 8 and surrounded by radiating flames 11, terminating in scroll-margins. 25

We claim—

The design for a gas-radiator, substantially as described and shown.

LAZARD KAHN.
ADAM SPECK.
